UNITED STATES PATENT OFFICE.

ADAM AMOS SERVA, OF CANTON, AND DAVID H. FRIEND, OF NORTH INDUSTRY, OHIO,
ASSIGNORS TO THE UNITED ELECTRIC COMPANY, OF CANTON, OHIO, A CORPORA-
TION OF OHIO.

DUST COLLECTOR.

Application filed March 1, 1923. Serial No. 622,118.

This invention relates to improvements in dust collectors for vacuum cleaners and is more particularly adapted for use upon a portable cleaner.

- 5 The objects of the invention are to provide a dust collector including a rigid tubular member into which the dust-laden air is exhausted from the fan, a bag which may be impervious being connected to the lower end 10 of the tube, to receive the heavy dirt and dust which enters the tube, while a pervious bag is connected above the tube to receive the lighter dust and to permit the air to escape through the walls thereof.
- 15 The above and other objects may be attained by providing a T-elbow connected to the outlet of the fan chamber, the upper and lower bags being connected to the opposite ends of the T-elbow which is flared from 20 the fan casing toward the bags to permit the air to expand.

A practical embodiment of the invention is illustrated in the accompanying drawings, in which—

- 25 Figure 1 is a side elevation of a truck type of vacuum cleaner provided with the improved dust collector, parts being broken away to show the interior construction; and Fig. 2, a top plan view of the same, the 30 upper dust collector bag being removed.

Similar numerals of reference indicate corresponding parts throughout the drawings.

- The invention is illustrated as applied to the truck type of portable vacuum cleaner 35 which includes the tank 1 supported upon the front wheels 2 and provided with the air inlet 3 communicating with the elbow 4 upon which is swivelled the nozzle 5 extended to one side of the front portion of the tank, 40 and provided with the casters 6 for engagement with the floor or other surface to be cleaned.

- An intake pipe 7 is connected to the air inlet, the inner extremity thereof being 45 directed upward toward the deflector 8 which is suspended from the upper portion of the tank as by the straps 9, a screen 10 covering the upper open end of the tank which communicates with the inlet 11 of the 50 fan chamber or snail 12 in which a suction fan 13 is located and arranged to be rotated by the motor 14 which is mounted above the snail.

This much of the construction may be

varied, and in itself forms no part of the 55 present invention. To the outlet neck 15 of the snail is attached a reduced extremity of the T-elbow 16, the enlarged, vertical portion 17 thereof being preferably located in the longitudinal center of the device as shown in 60 Fig. 2.

The lower dust collector bag 18, which may be impervious, is suspended from the lower end of the portion 17 of the T-elbow, being preferably connected thereto as by the 65 bayonet joint 19. The upper dust collector bag 20 which is preferably pervious, is connected to the upper end of the portion 17 as by the bayonet joint 21, the upper end of the bag being supported as by the arm 22, which 70 may be mounted upon the stationary portion of the truck.

The truck is arranged to be propelled over the floor by means of a handle comprising the U-shaped rod or pipe 23 connected at its 75 forward end to the tank and extending rearwardly and upwardly as at 24, a swivelled caster 25 being connected to the cross plate 26 upon the handle, for the purpose of supporting the rear portion of the device upon 80 the floor.

The dust laden air which is expelled from the snail expands as it passes through the flared T-elbow, relieving the pressure gradually as the air passes from the exhaust of 85 the snail to the vertical portion 17 of the T-elbow.

The air entering the portion 17, will expand upward and downward, the heavier dirt dropping into the lower bag 18, while 90 only the lighter particles of the dust will pass upward into the upper bag 20, the air escaping through the walls thereof. Some of the lighter dust will drop down into the lower bag, while some will be retained 95 upon the walls of the upper bag.

As the T-elbow is rigid, the air expelled from the exhaust of the snail into the portion 17, will be permitted to expand without bulging or distending the same, the air expanding 100 up and down within the vertical portion 17 of the T.

As the T-elbow is flared away from the exhaust of the snail, the air may expand rapidly as it passes through the elbow, relieving pressure therein.

When the machine is not in use, the walls of the upper bag may be shaken or tapped,

causing all of the dust adhering thereto to fall into the lower bag, which can be quickly detached and emptied whenever necessary.

We claim:—

5 A vacuum cleaner including a fan chamber with an exhaust opening at one side, an upright outwardly flared T-elbow communi-

cating with the exhaust opening and upper and lower dust collecting bags connected to opposite ends of the T-elbow and directly 10 behind the fan chamber.

ADAM AMOS SERVA.
DAVID H. FRIEND.
